UNITED STATES PATENT OFFICE.

JOHN NAZARIAN, OF PATERSON, NEW JERSEY.

MATCH-DISPENSING MACHINE.

1,294,824.

Specification of Letters Patent. Patented Feb. 18, 1919.

Original application filed March 25, 1918, Serial No. 224,521. Patent No. 1,292,853. Divided and this application filed September 23, 1918. Serial No. 255,281.

To all whom it may concern:

Be it known that I, JOHN NAZARIAN, a citizen of the United States, residing at Paterson, in the county of Passaic and State of New Jersey, have invented certain new and useful Improvements in Match-Dispensing Machines, of which the following is a specification.

This invention relates particularly to machines adapted to cut the tips from cigars and to dispense matches of the kind in which the mechanism is operated by a motor, such as a spring motor, in such manner that tips are severed from the body portions of cigars and matches are delivered singly from a hopper or other reservoir in which they are stored.

Cigar cutters or match dispensers of this general kind are used in cigar stores and drug stores and may also be used privately.

This application is a division of my application for patent, Serial No. 224,521, filed March 25, 1918, Patent Number 1,292,853.

In said application I have shown a combined cigar cutter and match dispenser in which a spring motor is provided for operating the cutting mechanism, said mechanism being set in motion by pressing the tip of a cigar against a suitable release device and at the same time the match-dispensing mechanism is actuated to deliver a match. Provision is also made for operating the cutting mechanism without bringing the motor mechanism into operation, and devices are employed for dispensing matches singly without operating the cutting mechanism. Provision is also made for delivering matches one by one without breaking the matches or without impeding the operation.

My application above referred to claims the novel features of the combined cigar-cutting and match-dispensing mechanism and also certain improvements in the cigar cutting mechanism separately considered. The claims in the present application are confined to the novel features of the match-dispensing mechanism.

The accompanying drawings show the combined mechanism and are substantially duplicates of those of my application for patent above mentioned.

Figure 1 is a perspective view of a com-

bined cigar cutter and match dispenser embodying my improvements. 55

Fig. 2 shows a transverse section on the line 2—2 of Fig. 6.

Fig. 3 shows a transverse section on the line 3—3 of Fig. 6. 60

Fig. 4 is a detail view in section showing the manner in which certain parts are operated by the spring motor.

Fig. 5 is a perspective view showing most of the mechanism within the casing, the casing being partly broken away to expose such mechanism. Fig. 5^a is a perspective view of portions of the match dispensing mechanism. 65

Fig. 6 is a top plan view of the mechanism within the casing, the top or upper portion of the casing being removed. 70

Fig. 7 shows a transverse section on the line 7—7 of Fig. 6.

Fig. 8 shows a section through the match hopper and associated mechanism on the line 8—8 of Fig. 6. 75

Fig. 9 is a perspective view of the agitator employed in the match-dispensing hopper for keeping the matches separated. 80

Fig. 10 is a detail view of a device for holding a match after being moved forward by the pusher and projected from the casing.

Fig. 11 is a perspective view of the holding device shown in Fig. 10. 85

Fig. 12 is a perspective view of the match pusher detached from the mechanism with which it co-operates.

Referring to Fig. 1, it will be observed that the casing 1 is provided with a hinged portion 2 and is equipped with a lock 2^a by means of which access to the interior of the casing above the match hopper may be obtained. A hole 3 is formed in the top of the casing to receive the tip end of a cigar when it is desired to remove the tip therefrom. Matches are ejected through a hole 4 in the front of the casing and a container 5 beneath the opening 4 may be provided to hold the matches after they have been used. 90 95

As will be hereinafter explained the match-dispensing mechanism and the cigar-cutting mechanism are preferably combined for conjoint operation, power being supplied by a spring or other suitable motor but provision is made for operating the cutter and dispenser separately when desired. 100 105

Referring now more particularly to Figs. 5 and 6 of the drawings, it will be observed that at one end of the casing supports 6 and 7 are attached in which is rotatably mounted a shaft 8 which projects through the casing as indicated, its outer end being suitably shaped to receive a key, by means of which the shaft may be turned to wind up the spring which in this instance is employed for providing the necessary power. The spring 12 is preferably a clock spring of ordinary construction, its inner end being secured to the shaft 8 at 10 and its outer end being attached to the casing at 11. A disk 14 and a ratchet wheel 15 are keyed to the shaft 8 adjacent the spring.

Loosely carried by the shaft 8 is a sleeve 16 to which is securely fastened a disk 17 and a gear wheel 18. The disk 17 carries a pawl 19 which engages the ratchet wheel 15. When the spring partially unwinds, the gear wheel 18 will be rotated in the ordinary manner.

A shaft 24 extending from one end of the casing to the other is mounted to rotate in supports 20, 21, and 22, and preferably both ends of the shaft are extended through the ends of the casing and are provided with handles 25, by means of which the shaft 30 may be turned when it is desired to operate the mechanism without bringing into operation the spring motor. Keyed to the shaft 24 is a pinion 26 meshing with the gear wheel 18 which is operated in the manner before described and by means of which the shaft 24 may be turned.

In Fig. 2 arrows indicate the relative direction of rotation of the two shafts: The shaft 24 carries an eccentric 30 which is keyed to the shaft and which is surrounded by an eccentric strap 31. Connected to the strap 31 is a rod 32 at the outer end of which is attached a tip cutting knife 33 which is held against the inner face of the top of the casing by a flat spring 34 which may be adjustably secured to the support 7 by a set screw 35. This spring bears against the rod 32 in the manner indicated in Fig. 3 and holds the knife against the under side of the top of the casing. When the eccentric 30 is turned with the shaft 24, the knife is reciprocated across the inside of the casing below the opening 3 and if the tip of a cigar has been inserted 55 through the opening it will be cut off by the knife.

In order to cause the tip-cutting knife to be reciprocated only once for each cutting operation or only each time that a cigar tip is inserted through the opening 3, I provide a detent mechanism adapted to permit the shaft 24 to be rotated only when a cigar is projected through the opening, said detent mechanism comprising a sleeve 37 loosely mounted on the shaft 8 and having two

arms 38 and 39. The outer end of the arm 38 carries a plate 40 normally held directly beneath the opening 3 and normally adjacent the inner face of the top of the casing. This may be done by a spring 41 applied to the arm 39 and having its opposite end suitably supported. The arm 39 is provided with a dog 42 normally engaging a shoulder 43 on a disk 44 fast on the shaft 24. When the end of a cigar is projected through the opening 3, the plate 40 is depressed and the arm 39 carrying the dog 42 is raised and disengaged from the shoulder 43 of the disk 44. When this is done the spring 12 operates to turn the shaft 24 one complete revolution. As soon as the tip of the cigar is severed from the body thereof, the knife withdraws and the plate 40 is automatically moved to its normal position by the spring 41 and the dog 42 is again brought into contact with the shoulder 43 of the disk 44. When the parts assume this position they are ready for another operation.

It will be observed that by this mechanism as soon as a cigar is inserted through the opening 3 the motor mechanism is released. The cutter operates to remove the tip and as soon as the tip is removed the cutting mechanism returns to normal position and the locking mechanism also returns to normal position. Only a single revolution is given to the actuating shaft at each operation. As shown in Figs. 2, 3, and 5, the support 21 for the shaft 24 is extended as indicated at 21^a to form a buffer for the dog 42 against which it rests when in normal position. In order that the rotation of the shaft 24 may be gradually checked, an eccentric disk or cam 46 is secured to the shaft and it is so positioned thereon that the portion of the cam having the longest radius is brought into frictional engagement with a flat spring 47 attached to a vertical support 48 a short time before the dog 42 is brought into engagement with the shoulder 43 of the disk 44. In this way any overthrow of the shaft and the shouldered disk is prevented.

The mechanism above described is associated with mechanism for dispensing matches, which latter mechanism is located near one end of the casing. 50 indicates a hopper or receptacle for matches which is of suitable dimensions to contain a suitable supply of matches of the desired length and this hopper is preferably located immediately below the hinged portion 2 of the casing. As indicated, the hopper is provided with ears 51 projecting from its opposite sides and supported on bars 52 extending across the casing below the hinged portion 2 or lid of the casing as best illustrated in Fig. 8.

The lower portion of the hopper is tapered

to form a neck or chute 54 which is of the same length as the hopper in order that it may properly receive matches supplied to it. The lower end of the chute is preferably extended rearward to a greater length than that of the hopper as indicated in Fig. 7. The chute portion 54 of the hopper is located above a V-shaped trough 55, the trough and hopper being so close to each other that only a single match can fall into the trough from the chute at any time. The trough is suitably supported as by plates 57 secured to the bottom of the inside of the casing. The trough 55 preferably extends only the length of the bottom of the hopper as illustrated in Fig. 7. The supporting plates 57, however, extend rearwardly sufficiently far to slidably support a pusher 58 which is adapted to be reciprocated beneath the hopper when the pusher is in its normal retracted position, that is when it is withdrawn from beneath the hopper.

The pusher illustrated in Fig. 12 is of V-shaped construction conforming substantially to the shape of the trough 55 in which it is adapted to slide. It is provided with guides 59 for engagement with the outer walls of the trough.

As illustrated in Fig. 12, I construct that portion of the pusher which moves under the walls of the hopper of thin metal in order that the sides of the chute 54 may be brought sufficiently close to the bottom of the trough 55 to permit only a single match to fall into the trough at any time. The rear end of the pusher is preferably provided with rounded projecting portions 60 and depending vertical pins 61. Normally the pusher 58 is held in position at the rear of the hopper as best shown in Figs. 6 and 7 by means of springs 62 connected with pins 61 and to the rear of the casing 1.

For moving the pusher forward to eject a match from the bottom of the trough 55 through the opening 4 as indicated in Fig. 7, I have provided eccentric disks or cams 65 which are secured to the shaft 24, the eccentric portions of these disks being so positioned that when the pusher 58 is in its normally retracted position it is nearest the shaft 24, but when said shaft is rotated the disks are also rotated and they engage the projecting portions 60 of the pusher, thereby moving the pusher along the trough beneath the hopper and thus advancing a match in the bottom of the trough and through the opening 4 in the front of the casing.

In order to prevent a match from falling before it is grasped and after it is ejected from the trough, I have provided a swinging member 67 which is pivoted to the inside of the casing. As shown in Fig. 10, said member has a semi-circular conical opening 67a through it, the largest radius of which is on its inner side adjacent the bot-

tom of the trough 55. Said member 67 normally rests on a lug 68 before it is elevated by the passage of a match through the conical opening. The weight of the member 67, bearing on the stem of the match, prevents it from falling after the pusher has completed its stroke, but the match may be easily withdrawn when desired.

Inasmuch as matches are often stuck together, I provide means for breaking them apart before they enter the chute portion 54 of the hopper 50, such means being also adapted to insure that the matches assume a substantially horizontal position in the chute. For this purpose a plate 70 is provided having a roughened portion 71 and being formed with a lug 72 projecting through a slot 70a in one wall of the hopper 50. The roughened surface 71 is preferably formed by a series of points positioned on the plate 70 at a level about where the chute portion is jointed to the body portion of the hopper. Mounted on the pusher 58 is a vertical cam or fin 73 adapted to engage the lug 72 and thereby move the agitator plate up and down as the pusher reciprocates. The agitator plate may be removably secured in the hopper by means of a movable bar 74 extending the length of the hopper and across the top thereof.

For the purpose of moving the pusher 58 independently of the spring mechanism for obtaining a match and without operating the cigar tip-cutting mechanism, I have provided a pull rod 75 carried by suitable supports 76 and provided with a knob 77. Secured to the rod 75 are one or more vertical arms 78 projecting upwardly back of the pusher 58. A spring 79 surrounding the rod 75 and engaging a collar 80 thereon tends to hold and return the rod to normal position. By merely pulling on the knob 77, the pusher 58 may be moved forward to discharge a match without bringing into operation the cigar-cutting mechanism or the power-actuated mechanism which is ordinarily used to operate the pusher.

A match may also be obtained by merely turning the handle 23 on the shaft 24. When this is done the mechanism will operate in the same manner as when driven by the spring 12, but in this instance the shaft 24 should be turned in the opposite direction as indicated by the dotted arrows in Fig. 5. When this is done the dog 42 will offer no obstruction to the operation of the shaft and during such operation the spring 12 will be partially wound.

It is sometimes desirable to sound some kind of an alarm when the mechanism is operated. As illustrated in the drawings, I have provided a bell which may be sounded every time the match-dispensing pusher moves forward. As illustrated, an arm 90 is arranged in the path of travel of a pro-

jection 60 on the pusher 58. Said arm is pivotally supported at its lower end and is connected to a bell clapper 81 for the bell 82. When the projection 60 of the pusher 5 is moved forward to rock the arm 90 the clapper 81 will be operated to sound the bell.

A spring 83 is provided for returning the arm 90 to its normal position.

- 10 The operation of the mechanism has been described in connection with a description of the details of construction illustrated and it will be understood that when preparing the mechanism for use the spring is wound 15 to the proper extent to cause the mechanism to be actuated many times. For instance, it may be wound each morning and may have sufficient power to cause the devices to operate as often as could possibly be required 20 during the day. Each time that the tip end of a cigar is inserted through the opening 3, the detent mechanism is released, the knife is advanced, severs the tip from the cigar, then the knife returns, the detent 25 mechanism locks the power-driven mechanism and said mechanism is ready for another operation. During this operation the match-feeding pusher is advanced and forces a single match through the opening 30 in the front of the casing, said match being held in position to be readily grasped when wanted. As soon as the match is thus projected, the pusher mechanism retreats and assumes the proper position for another operation.

While I herein claim particularly the mechanism for dispensing matches, such mechanism has been shown and described in connection with the mechanism for cutting the tips from cigars because such mechanism is closely related with the match dispensing mechanism, some parts of the match dispensing mechanism forming part of the cigar tip cutting mechanism.

45 Inasmuch as my invention embodies some broad features of novelty it should be understood that I do not wish to limit my claims to the details of construction shown. While the mechanism illustrated is efficient, 50 the drawings are intended to show only the preferred form of my invention being the best way now known to me of embodying it in operative mechanism.

What I claim is:

- 55 1. Match-dispensing mechanism, comprising a hopper in which the matches are stored, a chute through which the matches are delivered from the hopper, a trough which receives the matches from the chute, a 60 pusher movable over the trough and engaging the lowermost match in the chute to move it endwise in the trough, an operating shaft, a motor for revolving the shaft through a plurality of revolutions in the 65 same direction, means interposed between

the shaft and the pusher for connecting them and for moving the pusher forward to expel matches one at a time, and means for stopping the rotation of the shaft after each forward movement of the pusher.

70

2. Match-dispensing mechanism, comprising a hopper in which the matches are stored, a chute through which the matches are delivered from the hopper, a trough which receives the matches from the chute, a 75 pusher engaging the lowermost match in the chute for moving it endwise in the trough, an operating shaft, a motor for revolving the shaft through a plurality of revolutions in the same direction, a cam on the shaft 80 engaging the pusher for moving it forward to expel matches one at a time, and means for stopping the rotation of the shaft after each forward movement of the pusher.

85

3. Match-dispensing mechanism, comprising a hopper in which the matches are stored, a chute through which the matches are delivered from the hopper, a trough which receives the matches from the chute, a pusher engaging the lowermost match in 90 the chute to move it endwise in the trough, an operating shaft, a motor for revolving the shaft through a plurality of revolutions in the same direction, a cam on the shaft 95 engaging the pusher for moving it forward to expel matches one at a time, a spring for retracting the pusher, and means for stopping the rotation of the shaft after each forward movement of the pusher.

95

4. Match dispensing mechanism, comprising a hopper in which the matches are stored, a chute through which the matches are delivered from the hopper, a V-shaped trough below the chute which receives matches therefrom, a pusher provided with 100 guides engaging the side of the trough and adapted to engage the lowermost match in the chute to move it endwise in the trough, and means for reciprocating the pusher.

100

5. Match dispensing mechanism, comprising a hopper in which the matches are stored, a chute through which the matches are delivered from the hopper, a trough which receives the matches from the chute, a pusher engaging the lower-most match in 110 the chute to move it endwise in the trough, a motor-driven shaft, connections between the shaft and the pusher for moving the latter forward, and manually operated means for reversing the rotation of the shaft 115 to operate the pusher by manual power.

110

6. Match dispensing mechanism, comprising a hopper in which the matches are stored, a chute through which the matches are delivered from the chute, a trough which receives the matches from the chute, a pusher engaging the lower-most match in 120 the chute to move it endwise in the trough, a motor-driven shaft, detent mechanism for causing the shaft to turn only a single revolu- 125

130

- lution at each operation, means for releasing the detent mechanism to permit the shaft to turn, and connections between the shaft and the pusher for moving the latter forward.
7. Match dispensing mechanism, comprising a hopper in which the matches are stored, a chute through which the matches are delivered from the hopper, a trough which receives the matches from the chute, a pusher engaging the lower-most match in the chute to move it endwise in the trough, a motor-driven shaft, detent mechanism which permits the shaft to turn only a single revolution at each operation, a brake for retarding the rotation of the shaft, and connection between said shaft and the pusher for moving the latter forward.
8. Match - dispensing mechanism, comprising a hopper in which the matches are stored, a chute through which the matches are delivered from the hopper, a trough which receives matches from the chute, a pusher engaging the lowermost match in the chute for moving it endwise in the trough, an operating shaft, a motor for revolving the shaft through a plurality of revolutions in the same direction, means interposed between the shaft and the pusher for connecting them and for moving the pusher forward to expel matches one at a time, means for stopping the rotation of the shaft after each forward movement of the pusher, and a hand-operated rod connected with the pusher for operating the latter without bringing into operation said motor-driven shaft.
9. Match dispensing mechanism, comprising a hopper in which the matches are stored, a chute through which the matches are delivered from the hopper, a trough which receives the matches from the chute, a pusher engaging the lower-most match in the chute for moving it endwise in the trough, a motor-driven shaft, connections between the shaft and the pusher for moving the latter forward, a hand operated rod for moving the pusher without bringing the motor-driven shaft into operation, and an alarm bell operated by the pusher each time that it ejects a match.
10. Match dispensing mechanism, comprising a hopper in which the matches are stored, a chute through which the matches are delivered from the hopper, a trough which receives the matches from the chute, a pusher engaging the lower-most match in the chute to move it endwise in the trough, means for operating the pusher, an agitator plate arranged vertically in the trough and provided with projections engaging the matches therein, and means carried by the pusher for moving said agitator to separate matches while being delivered.
11. Match dispensing mechanism, comprising a hopper in which the matches are stored, a chute through which the matches are delivered from the hopper, a trough which receives the matches from the chute, a pusher engaging the lower-most match in the chute to move it endwise in the trough, means for operating the pusher, an agitator plate arranged vertically in the trough and provided with projections engaging the matches therein, a cam plate or fin carried by the pusher, and a projection in the agitator plate which is engaged by said cam plate or fin whereby said plate is moved in the hopper to separate matches being delivered therefrom.
12. Match dispensing mechanism, comprising a hopper in which the matches are stored and which is formed with an inclined bottom, a chute through which the matches are delivered from the hopper, a trough which receives the matches from the chute, a pusher engaging the lower-most match in the chute for moving it endwise in the trough, means for operating the pusher, a vertically arranged agitator plate carrying projections normally disposed at the junction of the bottom of the hopper with the top of the chute, and means carried by the pusher for operating said agitator plate.
13. Match dispensing mechanism, comprising a hopper in which the matches are stored, a trough to which matches are delivered from the hopper, a pusher engaging the matches as they are delivered from the hopper, means for reciprocating the pusher, and means for holding a match delivered by the pusher comprising a swinging weighted member pivotally connected with the front portion of the casing and formed with an opening through which the matches are delivered, the walls of which opening are beveled or inclined whereby said swinging member is raised when the front of a match, while being moved forward, engages said member, said member being weighted to hold a match in a projected position when it has been moved forward to its full extent by the pusher.

In testimony whereof, I have hereunto subscribed my name.

JOHN NAZARIAN.

Witness:

MAURICE SHEA.
